UNITED STATES PATENT OFFICE.

FELIX JOSWICH, OF ST. PAUL, MINNESOTA.

INTERNAL-COMBUSTION ENGINE.

1,069,432.

Specification of Letters Patent. Patented Aug. 5, 1913.

Application filed February 27, 1912. Serial No. 680,357.

To all whom it may concern:

Be it known that I, FELIX Joswich, a citizen of the United States, residing at St. Paul, in the county of Ramsey and State of Minnesota, have invented certain new and useful Improvements in Internal-Combustion Engines, of which the following is a specification.

My invention relates to improvements in internal combustion engines of the two-cycle type, one of its main objects being to create and employ a partial vacuum to scavenge the combustion chamber of burned out gases, and at the same time to draw into it a fresh charge of explosive mixture. The use of a vacuum for these purposes economizes power, assists in vaporizing the explosive mixture, makes it unnecessary to use a pump for forcing the explosive mixture into the combustion chamber under pressure, keeps a more perfect division line between the dead gases and the fresh charge, and more completely scavenges the combustion chamber of the gaseous products of combustion.

A further object of the invention is to provide a piston with a trunk extension sleeve which shall cover and uncover the inlet and exhaust ports, and make it possible to space these ports apart a distance approximately equal to the length of the sleeve and avoid dead pockets.

With these and other objects in view the invention consists in the construction, combination, and arrangement of parts hereininafter described and claimed.

In the drawings forming part of this specification, Figure 1 is a vertical section of the engine through the inlet and exhaust ports, taken on line $v-v$ of Fig. 4; Fig. 2 is a cross section on line $x-x$ of Fig. 1; Fig. 3 is a cross section on line $y-y$ of Fig. 1; Fig. 4 is a cross section on line $w-w$ of Figs. 1 and 6; Fig. 5 is a cross section through the registering ports of the piston sleeve and cylinder taken on line $z-z$ of Figs. 1 and 6; and Figs. 6, 7, and 8 are vertical sections on line $t-t$ of Fig. 4, showing the piston at different stages of its stroke.

In the preferred embodiment of the invention shown in the drawings, A represents the cylinder, B the vacuum chamber, 2 the crank case and 3 the cylinder head, which is projected inwardly into the cylinder so as to leave between its side wall and the side wall 4 of the cylinder a channel or recess

receive the sleeve 5 of the piston and enable it to telescope over the cylinder head. The cylinder head carries a spark plug 6 of usual construction. Working within the cylinder is a trunk piston C which drives the crank-shaft 7 through the medium of the connecting rod 8. The piston head 9 carries an upwardly or inwardly extending sleeve or trunk extension 5 which slides upon the inner side of the side wall of the cylinder, and telescopes over the inwardly projected cylinder head, as above stated. At its lower end, just above the piston head, the sleeve is formed with a row of ports 10, extending at intervals entirely around its periphery. These ports are arranged in position to register successively with two rows of correspondingly disposed ports in the cylinder, namely the outlet ports 11 opening into the exhaust manifold 12, and the ports 13 opening into the vacuum chamber B. At its lower or outer end the piston carries a laterally extending annular flange 14, which slides like a piston upon the inner side of the side wall 15 of the vacuum-chamber. This wall is concentric with the piston, and is spaced apart from it and from the short terminal portion of the cylinder which extends down below the exhaust manifold, so as to form a surrounding vacuum chamber. The annular flange 14 forms a movable bottom closure for the chamber and the bottom wall of the exhaust manifold forms the top closure therefor. Near its lower end the piston is formed with an annular or circumferential depression 16 wide enough to bridge over, and allow communication between, the exhaust ports 11 and the ports 13 when the piston is at the top of its upward stroke, as shown in Fig. 7.

Near the cylinder head 3 the cylinder is formed with a row of inlet ports 17, disposed at frequent intervals all around its periphery. These open into the inlet manifold 18. It will be seen that the sleeve 5 is of sufficient height to cover and seal the inlet ports 17 at all times except when it is at the bottom of its stroke, in the position shown in Figs. 1 and 6. It will also be seen that the ports 10 in the lower end of the sleeve 5 will register with the outlet ports 11, once when the piston is nearly at the end of its down stroke and again just after it has started back upon its up stroke, as shown in Fig. 8. It will also be seen that the interior

of the telescoping piston-sleeve 5 becomes the combustion chamber in which the explosive mixture is compressed and fixed.

In Fig. 7 the piston is shown at the top 5 of its upward or inward stroke, with the sleeve 5 telescoped over the cylinder head. When, now, the explosive mixture, which is held under compression between the piston head 9 and the cylinder head, is fired, the 10 piston will be driven down, or upon its outward power stroke. As it starts down it immediately closes the ports 13 which open into the vacuum chamber, and thereby seals that chamber against the admission of air or 15 other gases. As it continues its outward stroke the flange 14 also moves down or out away from the exhaust manifold, and thereby increases the height, and enlarges the size, of the vacuum chamber so as to create 20 in it a partial vacuum. When the piston reaches the position shown in Fig. 8, the ports 10 in the lower part of the sleeve will come into registration with the outlet ports 11, and part of the burned gases will escape 25 through them into the exhaust manifold. When the piston travels a little farther and reaches the position shown in Figs. 1 and 6, the inlet ports 17 will be uncovered and the exhaust ports 11 closed while the ports 10 30 in the sleeve 5 will register with the ports 13 into the vacuum chamber; so that most of the remainder of the burned gases in the combustion chamber will be drawn through the ports 13 into the vacuum chamber, while 35 a fresh charge of the explosive mixture, under atmospheric pressure only, will rush into the combustion chamber through the inlet ports 17 and manifold 18 to take the place of the displaced burned gases. When 40 the piston starts up again on its return or inward stroke, it will first close the inlet ports 17 and the ports 13 into the vacuum chamber; then, when the ports 10 come again into registration with the exhaust ports 11, 45 the remainder of the burned out gases, which are now under some compression owing to the upward movement of the piston head, will be almost all expelled through the ports 11 into the exhaust manifold. The piston 50 then continues its inward stroke with all ports closed, compressing both the new charge of explosive mixture in the combustion chamber and the burned out gases in the vacuum chamber, until the annular depression 16 uncovers both the ports 13 and the outlet ports 11, when practically all the dead gases in the vacuum chamber will escape through these ports into the exhaust manifold. The piston will then have reached 55 the top of its compression stroke and, after the explosive mixture in the combustion chamber has been fired, the cycle of operations already described will be repeated.

The cubical contents of the vacuum chamber is nearly equal to that of the combustion

chamber, the latter being slightly greater to allow for a certain constant residuum of un-expelled dead gases remaining in the bottom of the combustion chamber; and as the explosive mixture is let into the inlet manifold 70 in predetermined quantities it will at no time enter the vacuum chamber.

It will be seen that by creating a vacuum whereby to scavenge the combustion chamber of burned gases and at the same time to draw into it a new charge of explosive mixture, the incoming fresh gases will be drawn in the same direction as the outgoing dead gases, so that the gases will not oppose each other and cause an irregular admixture of the two kinds of gases, but there will be a true division line between them, so that the combustion chamber will be more completely scavenged of the dead gases. The division line is more perfectly maintained, and the flow of the incoming and outgoing gases kept more uniform, by arranging the inlet and outlet ports at frequent intervals entirely around the periphery of the cylinder. Furthermore, by the use of a vacuum whereby to draw the charge of explosive mixture into the combustion chamber, the explosive gas can be admitted at atmospheric pressure, and a force pump be done away with. A further advantage is that the partial vacuum in advance of the incoming fresh gases will assist in vaporizing the mixture.

Various modifications may be made in the details of the engine, without departing from the principle of the invention, the 100 scope of which is defined in the claims.

I claim as my invention:

1. An internal combustion engine comprising a cylinder having an inwardly projecting cylinder head and being formed with inlet ports near said cylinder head, a piston working within the cylinder and having an extension sleeve adapted to slide over the cylinder head and cover and uncover said inlet ports, said cylinder being formed with exhaust ports spaced apart from the inlet ports a distance approximately equal to the length of the sleeve and said sleeve being formed with ports just above the piston head, a vacuum chamber having ports communicating with said ports in the sleeve, and means actuated by the travel of the piston for creating a partial vacuum in said chamber, whereby simultaneously to scavenge the sleeve of burned gases and to draw 110 into it a new charge of explosive fuel.

2. An internal combustion engine comprising a cylinder having spaced inlet and exhaust ports, a piston working within the cylinder and having an extension sleeve 125 adapted to cover and uncover said inlet ports and being formed near the piston head with ports registering with said exhaust ports, and a vacuum chamber surrounding the piston on the other side of the piston 130

- head and having ports communicating with said ports in the sleeve, and means actuated by the travel of the piston for creating a partial vacuum in said chamber, said piston 5 being formed near its outer end with a circumferential depression spanning the ports in the vacuum chamber and the exhaust ports in the cylinder when the piston is at the end of its inward travel, whereby to 10 open communication between said ports for the expulsion of burned gases from the vacuum chamber into the exhaust ports.
3. An internal combustion engine comprising a cylinder formed with inlet ports 15 near the cylinder head and exhaust ports spaced apart from the inlet ports, a piston working within the cylinder and having an extension sleeve adapted to cover and uncover said inlet ports, and to receive charges 20 of explosive fuel, said sleeve being formed near the piston head with ports registering with said exhaust ports, means for exploding the sleeve-contained fuel, a vacuum chamber having ports communicating with 25 the ports in the sleeve, and means actuated by the piston in its outward travel for creating a partial vacuum in said chamber, whereby, when its ports register with the ports in the sleeve, to scavenge the sleeve of 30 burned gases and simultaneously to draw into the sleeve a fresh charge of fuel.
4. An internal combustion engine comprising a cylinder having an inwardly projected cylinder head, a piston working with- 35 in the cylinder and having an extension sleeve adapted to telescope over the cylinder head, said cylinder being formed with inlet ports near the cylinder head and with exhaust ports spaced apart from the inlet 40 ports a distance approximately equal to the length of the sleeve, and said sleeve being formed with ports just above the piston head, a vacuum chamber surrounding the piston on the other side of the piston head, and having ports adapted to register with 45 the ports in the sleeve, the piston being formed at its outer end with a piston like flange working within the vacuum chamber and adapted to create a partial vacuum 50 therein, whereby to draw the burned gases from the piston sleeve into the chamber, and means for ejecting said gases from the chamber into the exhaust ports.
5. An internal combustion engine comprising a cylinder formed with inlet ports 55 near the cylinder head and exhaust ports spaced apart from the inlet ports, a piston working within the cylinder and having an extension sleeve adapted to cover and uncover said inlet ports, said sleeve being 60 formed near the piston head with ports adapted to register with said exhaust ports, and a vacuum chamber surrounding the piston on the other side of the piston head and having ports adapted to register with the 65 ports in the sleeve, said piston being formed near its outer end with a circumferential depression, and with a piston like flange working within the vacuum chamber and adapted to create a partial vacuum therein, whereby 70 to draw the burned gases in the piston sleeve into the chamber when the sleeve ports are in registration with the ports in the vacuum chamber, and whereby to expel said gases from the vacuum chamber into the outlet 75 ports, when said depression in the cylinder arrives at a position opposite the ports in the vacuum chamber and the exhaust ports and permits communication between them.

In testimony whereof I affix my signature 80
in presence of two witnesses.

FELIX JOSWICH.
